CLAIM

The ornamental design for an insulated container, as
shown.

DESCRIPTION

FIG. 1 is a front right perspective view of an insulated
container, showing my new design;

FIG. 2 is a front left perspective view thereof, with the
door shown open;

FIG. 3 is a rear perspective view thereof;

FIG. 4 is a reduced front elevational view thereof;

FIG. 5 is a reduced side elevational view thereof, the
opposite side being a mirror image thereof;

FIG. 6 is a reduced top plan view thereof, the bottom
being unornamented.
